BOLT ANCHORING DEVICE

Filed Oct. 22, 1928

UNITED STATES PATENT OFFICE

CHARLES HARMON SHOOK, OF DAYTON, OHIO

BOLT ANCHORING DEVICE

Application filed October 22, 1928. Serial No. 314,145.

This invention relates to a bolt anchoring device and is designed more particularly for anchoring a bolt in a concrete structure.

In the construction of concrete buildings it is customary to embed in the concrete beams, or other parts of the structure, bolts by means of which the angle irons or other devices which support the bricks with which the structure is faced are secured to the concrete structure. In practice it is very difficult to so position the bolts that they will be in proper alignment with the bolt holes in the angle irons and to maintain the bolts in such positions while the concrete is being poured. As a result the bolts often are out of line with the bolt holes and it is necessary either to enlarge the existing holes in the angle iron or to form new holes therein. This not only requires a great deal of time and labor but it frequently seriously weakens the angle iron.

One object of the present invention is to provide means for anchoring a bolt or other attaching device in a concrete wall of such a character that the bolt may be adjusted with relation to the wall to properly position the same with relation to a bolt hole in the device which is to be attached to the concrete wall.

A further object of the invention is to provide an anchoring device which will be simple in its construction, easily installed and which may be produced at a relatively low cost.

Other objects of the invention will appear as the device is described in detail.

In the accompanying drawings Fig. 1 is a horizontal sectional view showing my invention embodied in a concrete wall; Fig. 2 is a vertical sectional view of the same; and Fig. 3 is a perspective view of the housing.

In these drawings I have illustrated one embodiment of my invention but it will be understood that this particular embodiment has been chosen for the purposes of illustration only and that the device may take various forms and may be used in various ways without departing from the spirit of the invention.

In the particular construction here shown the device comprises a housing 5 adapted to be embedded in the concrete beam or structure in which the bolt is to be anchored. This housing may be of any character suitable to provide a cavity in the face of the concrete structure. As here shown, it is formed of sheet metal, is substantially rectangular in form and has five walls, the sixth side of the housing being open. It is also preferably provided at the open side thereof with laterally extending flanges 6 which may be embedded in the concrete and which serve to properly position the housing therein. These flanges also provide means whereby the housing may be attached, by nails or otherwise, to the wooden forms so as to retain the housing in position during the pouring of the concrete. When the housing is embedded in the concrete structure the open side thereof is substantially flush with the face of the structure and a cavity is thus provided in the front face of the structure, this cavity being formed at approximately the location of a bolt hole in an angle iron 7 or other device which is to be attached to the concrete structure.

An anchor bar 8 extends through the cavity thus formed and has its end portions projecting beyond the walls of the cavity and embedded in the concrete so that the anchor bar will be firmly held in position. In the present instance, that portion of the anchor bar which extends through the cavity is arranged in substantially horizontal position and to this end the side walls of the housing are provided with openings 9 through which the anchor bar extends. These holes are so arranged that this intermediate portion of the anchor bar, which is within the cavity or housing, is spaced from both the top and bottom walls and the back wall of the cavity. The end portions of the anchor bar may be of any suitable shape and arrangement. Preferably the shape of the anchor bar is such that it can be readily inserted through the openings in the housing. In the present instance, a portion 10 of the anchor bar, which projects beyond one side of the housing, is bent rearwardly at an acute angle to the intermediate portion of the bar so as to provide a relatively thick por-

100

tion of concrete between the same and the front surface of the concrete structure. The other end portion 11 of the bar extends a short distance beyond the other side of the housing and is then bent rearwardly. A supporting member or finger 12 extends laterally from the rear portion of the housing and engages beneath the part 11 of the bar to support the anchor bar as a whole in the proper position with relation to the concrete structure. As here shown, this part 11 is inclined upwardly and rearwardly so as to provide a great resistance to the forward pull thereon.

The device for attaching the angle bar to the anchor bar may take various forms but is preferably in the form of a bolt 13 and is provided with means whereby it may be connected with the anchor bar at different positions within the housing or cavity, so that the outer end of the attaching device may be adjusted with relation to the concrete structure to properly position the same. The bolt here shown has at its inner end a hook shaped portion 14 of such a character that it may be hooked about and engaged with the intermediate portion of the anchor bar and may be moved lengthwise of the anchor bar throughout the width of the cavity and may also be moved about the axis of the anchor bar so that the outer end thereof, which projects beyond the open side of the cavity, may be raised or lowered. In this manner the bolt is provided with a relatively large range of adjustments to accommodate it to the position of the bolt hole 15 in the angle bar 7. In the form here shown the bolt is of such a character that it may be readily attached to or detached from the anchor bar but this is not essential to the operation of the device and the bolt might be permanently secured to the anchor bar before the latter is embedded in the concrete.

If desired, the housing may be provided with marks to facilitate the locating of the same with relation to the position which will be occupied by the angle iron, which, of course, is not placed in position until the concrete structure is finished. As here shown, the lateral flanges 6 of the housing are provided with small notches 16 arranged in a horizontal line which intersects the longitudinal center line of the bolt 13 when the latter is in a horizontal position.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a device of the character described, a housing adapted to be embedded in a concrete structure, having an opening in that side thereof adjacent to the surface of said

structure to provide access to the interior of said housing and having other openings in opposite walls thereof, an anchor bar mounted in the last mentioned openings, extending through said housing and having its ends 70 projecting beyond said housing and adapted to be embedded in said concrete structure, an attaching device having a hook shaped part to enter said housing and to have supporting engagement with that portion of said anchor 75 bar which is within said housing, said portion of said bar being so arranged with relation to the walls of said housing that the hook shaped part of said attaching device may be engaged about the same after said housing 80 and said bar have been embedded in said concrete structure.

2. In a device of the character described, a housing having an open front and having openings in the opposite side walls thereof, 85 an anchor bar comprising an intermediate portion and end portions extending at angles to said intermediate portion, one of said end portions being arranged at such an angle to said intermediate portion that said anchor 90 bar may be inserted lengthwise through the openings in said housing to position said intermediate portion thereof within said housing with the end portions of said bar projecting rearwardly, said housing and said anchor bar being adapted to be embedded in a concrete structure, and an attaching device having a hook shaped part to be inserted through the open front of said housing and to engage about said intermediate portion of 100 said anchor bar and movably support said attaching device thereon, said portion of said bar being spaced such distances from the top, bottom and back walls of said housing that 105 said part of said attaching device may be hooked about the same after said housing and said anchor bar have been embedded in said concrete structure.

In testimony whereof, I affix my signature hereto.

CHARLES H. SHOOK.
